UNITED STATES PATENT OFFICE.

CHARLES EDWARD ROCHAMBEAU, OF ST. JOSEPH, MISSOURI.

CAR-BRAKE-CONTROLLING MEANS.

1,377,628.

Specification of Letters Patent. Patented May 10, 1921.

Application filed November 22, 1919. Serial No. 339,887.

To all whom it may concern:

Be it known that I, CHARLES EDWARD ROCHAMBEAU, a citizen of the United States, and a resident of St. Joseph, in the County 5 of Buchanan and State of Missouri, have invented a new and Improved Car-Brake-Controlling Means, of which the following is a full, clear, and exact description.

This invention relates to railway car 10 brakes and has particular reference to certain improvements in that class of brakes covered by Letters Patent of the United States issued to me on the 11th day of February, 1913, No. 1,052,967.

15 Among the objects of this present invention is to improve the means for controlling the operation of the drum or winding spindle for the brake chain.

More definitely stated I provide in this 20 instance a positive securing means for the locking pawl coöperating with the ratchet wheel associated with said brake drum or spindle.

The foregoing and other objects of the 25 invention will hereinafter be more fully described and claimed and illustrated in the drawings forming a part of this specification in which like characters of reference indicate corresponding parts in all the views,

30 and in which—

Figure 1 is a side elevation of my improvement with the front wall or face plate, the hand wheel and the chain omitted;

Fig. 2 is a horizontal section on the line 35 2—2 of Fig. 1;

Fig. 3 is a horizontal view on the line 3—3 of Fig. 1; and

Fig. 4 is a vertical transverse section on the line 4—4 of Fig. 1.

40 The several parts of the device may be made of any suitable materials, and the relative sizes and proportions, as well as the general design of the mechanism, may be varied to a considerable extent without deviating from the spirit of the invention 45 hereinafter more fully set forth and specifically claimed.

Referring more particularly to the drawings, I show at 10 any suitable form or construction of casing adapted to be secured in 50 any desired position to a car body or frame as, for instance, through perforated flanges 11. Said casing includes a front panel 12 secured to the main portion of the casing by 55 nuts 13 or equivalent fastening devices.

Journalized in the casing transversely there-

of is a power shaft 14 having a pinion 15 mounted thereon. As a suitable means to operate the power shaft I show a hand wheel 16 secured to the end of the shaft 14 outside 60 of the casing. A brake drum or spindle 17 is journaled in the casing with its axis parallel to the shaft 14, and a large gear wheel 18 meshing with the pinion 15 is secured to said spindle.

65 Adjacent the gear wheel 18 is a ratchet wheel 19 with which coöperates a pawl 20 pivoted intermediate its ends at 21 on an axis parallel to the aforesaid axes. The tail 22 of the pawl extends upwardly at an angle 70 to the longitudinal axis of the pawl and is of sufficient weight to substantially counter-balance the weight of the pawl.

Any suitable means may be provided to 75 control the action of the pawl either to throw it into or out of locking engagement with the ratchet wheel 19. The means I prefer to use for this purpose includes a weight 23 slidable freely along a guide rod or bar 24 extending along the casing parallel to the normal longitudinal axis of the pawl. The weight 23, to provide for the free slidable movement both longitudinally and vertically of said bar 24, is formed with a slot 25 of considerably greater width than the width 85 of the bar. The lower end or point of the weight is adapted to bear upon the upper portion of the pawl for the purpose of causing the pawl to engage the ratchet wheel. By sliding the weight, however, along the 90 bar 24 so as to cause it to ride upon the tail 22 of the pawl, the pawl will be thrown and held out of locking engagement with the ratchet wheel. In order to control the movement or action of the weight 23, I connect 95 thereto a link 26, the same extending substantially parallel to the bar 24 and beyond one side of the casing where it terminates in a finger piece 27 of any suitable construction. The connection between the link and the 100 weight is preferably a pivot 28. The finger piece is provided with a transverse hole adapted to align with a similar hole formed in a lug 29 formed integral with or secured to the adjacent side wall of the casing 105 whereby, by the use of a padlock P or the like the weight 23 may be locked in the position required for locking the pawl positively in engagement with the ratchet wheel, as shown in Fig. 1.

110 From the foregoing description of the principal parts of this mechanism, it will be

understood that a brake chain 30 which may enter the casing through an opening 31, and having its inner end secured at 32 adjacent the spindle 17, may be tightened by rotation 5 of the hand wheel in the direction of the arrow shown in Fig. 2. When the brake is set in the manner set forth, the weight 23 will be shoved inwardly so as to depress the pawl 20 and lock it in engagement with the ratchet 10 wheel. Then, if desired, the pawl controller 15 may be locked in position so as to prevent any unauthorized party from tampering with the brake after it has been set and locked. By providing the weight 23 with a wide slot 25, I insure that the full weight of 20 the weight will bear at all times upon the pawl.

Having thus described my invention, I claim as new and desire to secure by Letters 25 Patent:—

1. In a device of the character set forth, the combination of a brake casing, a power spindle journaled transversely therein, a 30 brake chain extending through the wall of the casing and connected to said spindle, a ratchet wheel secured to the spindle, a pawl coöperating with the ratchet wheel, a fixed bar extending within the casing parallel to the pawl, a weight slidable along said bar 35 and bearing at all times upon said pawl, and

a link connected to the weight and extending through and beyond the casing wall whereby the position of the weight may be controlled.

2. The combination of a brake casing, a 35 power spindle journaled in the casing, a 40 brake chain connected to said spindle, means to rotate the spindle, a ratchet wheel secured to the spindle, a pawl connected with the ratchet wheel and extending transverse to the axis of the spindle, a rigid bar secured in fixed position within the casing and substantially parallel to the pawl, a weight having loose slidable engagement with said bar and having its point bearing constantly upon the upper portion of the pawl, a link 45 loosely connected at its inner end to the weight and having its outer end provided with a finger piece on the outside of the casing whereby the position of the weight may be determined, and means for locking the 50 finger piece in definite position to the casing and thereby preventing the release of the pawl when the brake is set.

In testimony whereof I have signed my name to this specification in the presence of 55 two subscribing witnesses.

CHARLES EDWARD ROCHAMBEAU.
